(57) **CLAIM**

What is claimed is the ornamental design for jewelry, as shown and described.

DESCRIPTION

FIG. 1 is a perspective view of jewelry, showing my new design in use;

FIG. 2 is a front elevational view thereof, shown in a straight configuration, and shown at a reduced scale;

FIG. 3 is a rear elevational view of FIG. 2;

FIG. 4 is a right-side elevational view of FIG. 2;

FIG. 5 is a left-side elevational view of FIG. 2;

FIG. 6 is a top plan view of FIG. 2; and,

FIG. 7 is a bottom plan view of FIG. 2.

The broken lines showing a person in FIG. 1 are included for the purpose of illustrating the invention in use, and form no part of the claimed design.
